D. GUELBAUM.
CLOSED HIGH TEMPERATURE GAS BURNER.
APPLICATION FILED JAN. 5, 1921.

Patented Aug. 23, 1921.

INVENTOR.
David Guelbaum.

UNITED STATES PATENT OFFICE.

DAVID GUELBAUM, OF SYRACUSE, NEW YORK.

CLOSED HIGH-TEMPERATURE GAS-BURNER.

1,388,460.

Specification of Letters Patent. Patented Aug. 23, 1921.

Application filed January 5, 1921. Serial No. 435,185.

To all whom it may concern:

Be it known that I, DAVID GUELBAUM, a citizen of the United States, and a resident of Syracuse, in the county of Onondaga and 5 State of New York, have invented a Closed High-Temperature Gas-Burner, of which the following is a specification.

This invention has for its object a gas burner that gives higher temperatures with 10 less gas consumption than all now existing burners. To obtain such higher efficiency the burner is so designed, that, when combined with the container or utensil to be heated, a thoroughly insulated and closed 15 space is formed, like the combustion chamber of a modern boiler plant.

The air and gas mixture, ready to be ignited, enters a circular cone-beveled slot in 20 the center of that closed space, in the shape of a continuous conical sheet stream, the thickness of which can be regulated as desired.

Previous to entering the closed space, the air and gas are mixed and proportioned, by 25 means of a mixing and proportioning valve, in just the right ratio, corresponding to the maximum temperature of the resulting combustion gases.

The outlet for the products of combustion 30 from that closed space takes place through the circumferential clearance between the rim of the burner body and the bottom of the container or utensil; said clearance, being adjustable, may be closed entirely, or 35 opened up as much as required for the outlet of the combustion gases, but without permitting outside air to get into the closed combustion chamber.

The invention consists in the above set 40 forth novel features, embodied in the combinations and constructions hereinafter set forth and described.

In describing this invention, reference is had to the accompanying drawings, in which 45 like characters designate corresponding parts in all the views.

Figures 1 and 2 are respectively, a vertical sectional view and a top view, or plan, of my closed high-temperature gas burner.

50 Figs. 3, 4, 5, 6, and 7 and 11 are details of the various parts of my invention.

Figs. 8 and 9 show the adaptation of my invention to the melting of metals.

Fig. 10 shows its adaptation to temperature-efficiency tests.

This closed burner comprises generally a

hollow base or frame, shown in section on Fig. 1, and consisting of a rim 1 with a recess or well 2 in the center, rim and well being connected together by the radial ribs 3. 60

The intermittent spaces between the ribs are filled flush to the top of rim and well with heat insulating composition (not shown on the drawing) resting on the bottom plate 4, made preferably of light sheet metal and fastened to the bottom flange of the rim and to the bottom of the well, as shown in detail on Fig. 7.

The bottom of the well 2 is provided with a hub 5 carrying a revolving pivot 6, the bottom of which is joined fast to the lever 7 and to the locking washer 8 by means of the tap bolt 9 and two pins, which are screwed into the pivot 6 through the lever and the washer, as seen on Fig. 1 and in separate detail on Fig. 3.

After the tap bolt 9 is screwed tight into the pivot 6, the edge of the locking washer 8 is bent up against one of the flats of the hexagon head of the tap bolt 9, thus preventing the bolt from turning relative to the pivot and getting loose.

The other end of the lever 7 is bent up around the bottom flange of the rim 1, as shown on Fig. 1. By swinging the lever 7, 85 the pivot 6 is turned inside the burner one way or the other, or kept stationary at any position.

At its top the pivot 6 is provided with a pin 10 the ends of which pass through two 90 opposite inclined slots on the sleeve 11, which is slidingly fitted on the pivot 6, as shown on Figs. 1 and 3 and in development on Fig. 4.

The vertical portions of the slots shown 95 on Fig. 4 are provided for convenience of assembling, as will be explained hereinafter.

The sleeve 11 fits tight into the hub 12 of the central valve 13, both—sleeve and valve—being setscrewed together immovably, as shown on Figs. 1 and 3.

The top of the well 2 and the top of the valve 13 are both cone beveled and fitted concentrically into each other.

The valve 13 is provided with a lug 14 105 at its bottom, fitting between two lugs 15 on the well 2, as shown on Figs. 1, 3 and 5; thus, the valve 13 and the sleeve 11 are prevented from turning, but are free to move up or down.

Therefore, by swinging the lever 7 one 110 way or the other and thus turning the pivot

6 with the pin 10, the latter will slide along the inclined slots in the sleeve 11, pushing the sleeve with the valve up or down and thus opening or closing the concentric conical passage between the valve and the well.

The pivot 6 is provided with two pin holes at 90° to each other for changing the position of the lever 7 to suit location, where required.

10 On Fig. 1 the valve 13 is shown in its highest position, with the conical passage fully open.

The swing of the lever 7 is limited by the two stops 16 and the stop 16^a, located as shown on Fig. 2 in plan, and consisting of T-headed bolts with the nuts and locking washers inside the burner, as shown on Fig. 7.

Normally the valve 13 is held fast in its position, against the upward pressure of the gas, by the pin 10 in the pivot, as on Figs. 1 and 3. In order to take the valve out of the well, the lever 7 is sprung upward, passed over the stop 16 and brought close to the stop 16^a Fig. 2. In that position the ends of the pin 10 come right over the vertical portions of the slots shown on Fig. 4, and the valve with the sleeve can be lifted out of the well.

30 When the valve is returned to its seat, the lever is sprung back to its position between the two limiting stops 16.

Graduation marks on the face of the flange, along which the end of the lever 7 slides, indicate the exact position of the central valve and the size of the opening of the concentric conical passage as shown on Fig. 8.

40 The hollow space inside the valve 13 is filled with heat insulating composition, like that of the burner body.

The well 2 is connected with the outside wall of the burner by the preferably tapered nozzle 17, cast into the body of the burner, as on Figs. 1 and 2, and surrounded by the heat insulating composition.

45 Into that nozzle 17 is screwed in the connection fitting 18, provided with a threaded nipple 19 for a gas pipe connection and with air openings and an air shutter 20, for air inlet and its regulation.

50 Thus, the combustion mixture of gas and air, ready for ignition, enters at the bottom of the well 2 and passes through the concentric conical passage between the valve and the well in the form of a concentric conical sheet stream of any desired thickness.

55 The radial ribs 3 Figs. 1 and 2 partly project above the top face of the burner frame, for supporting the container or utensil 20 Fig. 1 to be heated.

60 As seen from the vertical section of the burner, Fig. 1, the space between the bottom 65 of the container or utensil and the top face

of the burner is closed, and abstraction of heat from the flame by the surrounding air is thus prevented, and as the burner and valve bodies are filled with heat insulating composition, as previously mentioned, the 70 outside surface of the burner will remain comparatively cool, and loss of heat by radiation and from contact with outside air will likewise be prevented.

Around the burner rim 1, at its top, is 75 slidingly fitted a ring 21 preferably made of a light sheet metal strap with the ends welded or riveted together, as shown on Fig. 1 and in development on Fig. 6.

The ring is provided with three inclined 80 projections, sliding on the lugs 22 cast on the outside of the burner, as shown on Figs. 1 and 6, thereby raising or lowering the ring 21 and thus closing up or opening the circumferential passage for the exhaust between the container 20 and the top face of the burner. On Fig. 1 that passage is shown only half open.

Graduation marks on the inclined projections of the ring show its exact position 90 and the size of the exhaust outlet at any time.

95 As shown on Fig. 6 one of the inclined projections is provided with two lugs limiting the swing of the ring, and at the middle of each projection there is a small flap 23 cut out of the strap and bent up to serve as a grip for swinging the ring.

In case the bottom of the container or utensil is smaller or larger in diameter than 100 the outside diameter of the burner, then a plate ring 24 is provided, shown in dash and dot on Fig. 1, supported by the ring 21 and raised or lowered together with that ring.

105 The valve 13 and the sleeve 11 are provided with a few teeth or projections 25 at their top, as shown on Figs. 1, 2, 3 and 4, for the purpose of preventing the formation of a closed pocket inside the sleeve, just 110 above the pivot 6, and also for supporting very small utensils to be heated.

The burner is provided with four lugs 26 cast on the body, as shown on Figs. 1 and 2, with pins 27 screwed into these lugs and 115 slightly riveted over. These pins serve as legs for supporting the burner, or they may be replaced by separator bolts for fastening the burner to a permanent table stand.

120 Figs. 8 and 9 show the adaptation of the closed burner to the melting of metals. The burner is the same as on Fig. 1, and is shown in elevation with the exhaust exit regulating ring in section; but instead of a container or utensil closing up the space over 125 the burner, a spherical insulated dome is here used with a melting pot inside.

130 A sheet metal jacket surrounds the dome, the intermittent space being filled up with heat insulating composition. The dome is

provided at its top with a lifting ring and two washers for fastening the jacket, and at its bottom inside it has three lugs 28 resting on the top of the burner and fitting 5 around the ribs 3, as shown on Fig. 9.

In order to obtain the highest possible temperature the gas and air connection fitting 18, shown on Figs. 1 and 2, is here replaced by an automatic gas and air mixing 10 and proportioning valve, which combines the air and gas in a fixed quantitative ratio conducive to the highest temperature, and for which a separate patent application has been made by same applicant.

15 Fig. 10 shows partly the application of the closed burner to temperature-efficiency tests for various gas and liquid fuels. The dome and burner here used are the same as on Fig. 8, with the only difference that the dome is 20 provided with a mercury well for receiving the thermometer, and with the lifting plate 29.

25 The same dome without the insulating jacket, but provided with surface ribs inside and outside for rapid heat absorption and transmission, may serve as a regular room heater.

30 The above described closed high temperature gas burner may be used singly, or several may be piped up together in a battery and fastened to a proper stand, or installed in existing stoves and ranges.

35 The advantages claimed for this burner over those now existing are:

1. The variability of the flame aperture and of the exhaust outlet, both made adjustable by wide handy movements, will conduce to more efficient and rapid heat transmission.

40 2. The combustion space in my burner being closed, the exhaust gases exit regulated, and the outside air prevented from entering the combustion space, there will be no abstraction of heat from the flame by its being exposed to open contact with the surrounding air, as is the case in now existing burners. Hence, my burner will give a higher flame temperature and a more rapid heat transmission, with the consequent saving in time and fuel.

45 3. There is no loss of heat by radiation or through contact with outside air from the burner surface exposed to hot combustion gases, my burner being closed and thoroughly insulated; thus, in my burner, more heat will be saved and transmitted.

50 4. The direct regulation of the flame aperture, without changing the entrance pressure and velocity of the combustion mixture, will result in a steady flame and prevent rebounding of same with escape of part of the combustion mixture unburned through the air openings, as may be witnessed by the smell of gas in existing burners.

55 5. The thorough insulation in my burner of the nozzle for admission of the combustion

mixture, from the point of its entrance to the very point of its outlet into the closed space under the container, will keep the entering combustion mixture stream far below its ignition temperature, and no premature ignition can take place.

6. The gradual widening and narrowing of the entering combustion mixture stream effected in my burner will prevent impacts and rebounds of the stream with its consequent partial escape unburned through the air openings, as witnessed by the gas smell in present burners.

10 In cases where it is desired to have a flame aperture of a constant and fixed size, 80 then the construction of the valve and pivot is simplified, as shown on Fig. 11, where the sleeve is left out, and the hub 12 of the valve is screwed on direct to the pivot 6 and is setscrewed to same immovably in any desired 85 position.

15 The pivot is fastened in the hub 5 of the well with a tap bolt and locking washer, the same as in the previous case, but with the regulating lever omitted.

90 What I claim is:

1. A closed high temperature gas burner, comprising a hollow base or frame with a rim and radial ribs supporting a well or recess in the center, having a cone beveled top 95 and a blank bottom with a hub in its center, a nozzle from the rim to the well, means for closing up the open space between rim and well against access of the surrounding air, a central valve with a cone beveled top 100 concentric with the cone beveled top of the well and having a hub in the center, means for raising and lowering the valve, thus opening or closing the concentric passage between well and valve, substantially as and 105 for the purposes specified.

2. A closed high temperature gas burner, comprising a hollow base or frame with a rim and radial ribs, a well in the center, a nozzle between the rim and the well, and a 110 plate closing up the open spaces between the rim and the well and fastened or cast on to the same, a central valve with a hub in the center, and a sleeve fitted and setscrewed into the hub and having two opposite oblong slanting slots, means for raising and lowering the sleeve with the hub and the valve for opening or closing the concentric passage between the well and the valve, substantially as and for the purpose described.

115 3. A closed high temperature gas burner, comprising a hollow base or frame with a rim, radial ribs, a well in the center, a closing plate, a nozzle between the rim and the well, a central valve with a hub, a sleeve 125 fitted and secured into the same and having opposite slanting slots, and a rotative pivot supported in the hub of the well and fitted slidingly into said sleeve and provided with a pin whose ends enter the opposite slots of 130

the sleeve, thus raising and lowering sleeve and valve, substantially as and for the purpose set forth.

4. A closed high temperature gas burner, 5 comprising a hollow base or frame with a rim, radial ribs, a well and a closing plate, a central valve with a lug at its bottom fitting between two similar lugs on the inside of the well to prevent the valve from turning but 10 leaving it free to move up or down, a pivot inside the hub of the valve, and a lever having one end fastened to the bottom of the pivot and its other end extending to the edge of the rim and passing around the bottom 15 flange on the same, for operating the pivot, sleeve and valve, the swing of the lever being limited by provided stops and its position indicated by graduation marks, substantially as and for the purpose described.
- 20 5. A closed high temperature gas burner, comprising a hollow base or frame with a rim, radial ribs, a well, a nozzle between the rim and the well, a closing plate, a central valve with pivot and lever, and a cylindrical 25 plate ring slidingly fitted around the top of the rim and having slanting oblong projections resting on lugs on the outside of the rim and provided with suitable stops and grips for rotating the same around the rim 30 and thereby raising or lowering it to the desired position, substantially as and for the purpose specified.

- 35 6. A closed high temperature gas burner, comprising a hollow base or frame with a rim, radial ribs, a well, a nozzle between the well and the rim, and a connecting piece

screwed into the outer end of the nozzle and provided with air inlet openings, air shutter and a threaded hub with a nipple for a gas inlet connection, substantially as and for the 40 purpose described.

7. A closed high temperature gas burner, comprising a hollow base or frame with a rim and radial ribs supporting a well or recess in the center and projecting partly 45 above the top face of the rim and the well, a closing plate, a central valve with hub, pivot and lever, a cylindrical plate ring with suitable supports, stops and grips, and a flat plate ring, carried on top of the cylindrical 50 plate ring and having an outside diameter to suit the diameter of the container to be heated, substantially as and for the purpose set forth.

8. A closed high temperature gas burner, 55 comprising a hollow base or frame with a rim, radial ribs, a well or recess in the center, a nozzle between the well and the rim with a gas and air supply connection attached, a closing plate, a central valve with 60 pivot and lever, a cylindrical plate ring with a changeable flat plate ring on top, and with lugs cast or fastened on the outside of the frame or rim and with pins of any desired length screwed and fastened into these lugs, 65 to serve as supporting legs for the burner frame, substantially as and for the purpose described.

In testimony whereof, I have hereunto signed my name, at Syracuse, in the county 70 of Onondaga, and State of New York.

DAVID GUELBAUM.
